(57) **CLAIM**

The ornamental design for a walk around elevating tub, substantially as shown.

DESCRIPTION

FIG. 1 is a perspective view of the bath tub of this invention in an elevated position, taken from a front corner.

FIG. 2 is a perspective view of the tub of FIG. 1 taken from the corner diagonally opposite to that of FIG. 1.

FIG. 3 is a plan view of the tub of FIG. 2.

FIG. 4 is an end elevation view of the tub of FIG. 2; and, FIG. 5 is a side elevation view of the tub of FIG. 2.

The broken line showing an elevating unit is included for the purpose of illustrating a portion of the bathing tub that forms no part of the claimed design.
